CONTROL CIRCUIT

Stanley Guzskie, Broadview, Clarence J. Holpuch, Chicago, and Meyer Marks, Clarendon Hills, Ill., assignors to Admiral Corporation, Chicago, Ill., a corporation of Delaware

Filed June 2, 1958, Ser. No. 739,374
4 Claims. (Cl. 179—1)

This invention relates generally to power control switches and more particularly to means for controlling remotely the power delivered to a load, such as, for example, a speaker.

There are in the prior art many different examples of remotely controlled power control circuits. Some of these control circuits function to change the bias on a vacuum tube; others function to vary an impedance connected in parallel with the utilization means, and others employ more elaborate schemes.

It is desirable, when supplying a signal from a source to a utilization means (such as a speaker), to match the output impedance of the signal source with the input impedance of the utilization means in order to obtain maximum power transfer and to minimize distortion. In systems employing a variable impedance connected across the input terminals of the load, it is desirable to maintain the matching of such impedances as closely as possible while altering the amount of power supplied to the utilization means. While many of the prior art remote volume control systems function to change the amount of power supplied to the speaker (or other utilization means) only the more elaborate systems function to maintain a near constant load input impedance (to match the power source output impedance) and thus minimize distortion.

An object of the present invention is to provide a simple system for remotely controlling the power delivered to a speaker or other utilization means but which minimizes distortion.

A second object of the invention is to provide means for controlling remotely the power delivered from a signal source to a utilization means while maintaining, within fairly close tolerances, the overall impedance presented to the signal source.

Another aim of the invention is a remote volume control of simple construction but capable of maintaining, in combination with the speaker impedance, an impedance which substantially matches the impedance of the audio signal source.

A fourth object of the invention is the improvement of power control systems generally.

In accordance with the invention there is provided first impedance means connected to a first input terminal of the utilization means and in series therewith. A switch having first and second stationary contact means and a first movable contact is constructed and arranged to shunt said first impedance means when said movable contact is closed on said first contact means. Located remotely from the utilization means are third stationary contact means, second impedance means having a plurality of contactable points thereon, a second movable contact constructed and arranged to contact selectively said third contact means or any of said contactable points on said second impedance means, means for connecting said third contact means to said first contact means to enable shunting of said first impedance means from the remote position, means for connecting said second movable contact to said second contact means, and means for connecting one end terminal of said second impedance mean to the second input terminal of the utilization means.

In accordance with a feature of the invention a step-

2

ping switch can be employed to control the position of said second movable contact, and the stepping switch in turn can be controlled by the combination of a small portable transmitter or signal generator which can be carried around by an operator and means responsive to the signal output of said transmitter to produce a signal for operating said stepping switch. Such an arrangement eliminates the necessity for connecting conductors between the remote control unit and the speaker since all the elements except the portable transmitter can be located near the utilization means (the speaker when the device is employed as a volume control).

The above mentioned and other objects and features of the invention will be understood more fully from the following detailed description thereof when read in conjunction with the drawings in which:

FIG. 1 is a schematic sketch of a preferred embodiment of the invention;

FIG. 2 is a schematic sketch of an alternative form

20 of the invention;

FIG. 3 is a combination block diagram and schematic sketch of another form of the invention; and

FIG. 4 is a modification of the circuit of FIG. 1.

It is to be understood that the invention about to be described has many applications and that one of the more common applications is as a volume control. In order to facilitate a clear understanding of the invention, it will be described in terms of such an application.

Referring now to FIG. 1, audio signal source 10 can comprise a radio receiver, a public address system, or in general, any system capable of producing electrical signals in the audio range. Such signals are supplied to a speaker 11 through the transformer 12 and the switching circuit enclosed in the block 13. It is this 30 switching circuit which constitutes the invention.

The switching circuit is composed of two sections 21 and 22 of which section 22 can be located near the speaker 11 and of which section 21 can be located at a point remote from the speaker, as, for example, in an operator's hand across the room from the speaker. Alternatively the section 21 can be located near the speaker and, in turn, can be controlled by some means located at a point remote from the speaker. In the section 22, the resistor 14 is connected in series with the speaker impedance 29.

Single pole, double throw switch 16 which comprises stationary contacts 18 and 19 and movable contact 17, is constructed and arranged so that when the movable contact 17 is closed on the contact means 19 (herein called "manual position") the resistor 14 will be shunted thereby. When the resistor 14 is so shunted, the speaker 11 will receive full power from the audio signal source 10. It is to be noted that while the movable contact 17 is closed on contact 19, the section 21 can have no effect on the amount of power supplied to the 50 speaker 11 since there can be no complete circuit between sections 21 and 22.

However, when the movable contact 17 is closed on the contact 18 (remote control position) a complete circuit is created between the sections 21 and 22 regardless 60 of the position of movable contact 23 of the section 21. More specifically, when the movable contact 23 is closed on stationary contact A the resistor 14 is shunted by a circuit including conductor 24, movable contact 23, conductor 26, and movable contact 17. When the movable contact 23 is closed on stationary contacts B, C, and D there is respectively, a 5.6 resistance (resistors 27 and 28), a 1 ohm resistance (resistor 28), and a short circuit through conductor 41, placed in parallel with the speaker winding 23.

It will be apparent that when movable contact 23 is closed on contact A, the full power output from the audio signal source 10 will be supplied to the speaker 23 and

that when the movable contact is closed on contacts B and C, decreasing amounts of power are supplied to the speaker 11. In position D, of course, no power is supplied to the speaker.

The values of the resistors 27 and 28 and resistor 14 are selected so that the overall impedance looking into the terminals 31 stays within fairly close limits for any combinations of positions of movable contacts 17 and 23. Since this overall resultant impedance is fairly close to the impedance of the speaker 11, signal distortion can be kept at a minimum for all of the volume levels.

With a speaker impedance of 3 ohms, with resistors 27 and 28 having values of 4.6 ohms and 1 ohm respectively, and with movable contact 17 closed on remote position contact 18 the impedances presented to the terminals 31 as the movable contact 23 is closed on contact positions A through D are as follows.

Contact position	Impedance
A	3
B	4.65
C	3.45
D	2.7

Referring now to FIG. 2, there is represented an alternative form of the circuit within the block 21' in which parallel arranged resistors 32 and 33 are employed in lieu of the series arrangement shown in the block 21 of FIG. 1. The leads 24', 26', and 41' of FIG. 2 connect to the same points as the corresponding leads 24, 26 and 41 of FIG. 1. In its operation, the circuit of FIG. 2 is the same as the circuit of FIG. 1.

In the previous descriptive material, it has been assumed that the portion of the circuit within the blocks 21 of FIG. 1 or 21' of FIG. 2 would be located at a point remote from the television, radio, or other speaker to enable an operator to control the volume from such remote point.

However, owing to the fact that section 21 contains only one movable contact (23), it has been found convenient to locate the section 21 in the receiver being employed and to operate the movable contact 23 by some other remotely located means such as a transmitter. More specifically, in FIG. 3, a transmitter 34, which may be constructed, in response to an act of an operator, to produce sonic waves or electrical waves, or may even be connected to a receiver-transducer 37 by conductors, can be located remotely from the section 21". Receiver-transducer 37 is constructed to respond to the output signal 36 of said transmitter to produce a signal which will operate stepping switch 38. Stepping switch 38 is linked mechanically with the movable contact 23" so that with each step of the stepping switch 38, the movable contact 23" will rotate to disengage with a given one of contacts A", B", C", or D" and to close on the next consecutive contact.

Referring now to the circuit of FIG. 4, there is shown an alternative form of the circuit of FIG. 1. The end terminal of the resistor 28" is connected directly to a terminal of the speaker through conductor 41''' and the stationary contact D''' is connected to the control grid of an audio amplifier tube (not shown), thus grounding said control grid and preventing any audio signal from reaching speaker 11.

More specifically the aforementioned control grid will be grounded, when movable contact 23" is closed on contact D'', in a circuit extending through conductor 40, movable control 23''', conductor 26, movable control 17, and the speaker winding 29.

A stepping switch suitable for use herein is described in application Serial Number 739,324, filed June 2, 1958, now U.S. Patent No. 2,990,723 of July 7, 1961, by Clarence J. Holpuch and entitled Stepping Switch, and which is incorporated herein as a part of this specification.

It is to be noted that the forms of the invention herein

shown and described are but preferred embodiments thereof and that various changes can be made therein without departing from the spirit or scope thereof.

We claim:

- 5 1. In combination; a source of electrical signals; a transducer for converting said signals into acoustic energy; a transformer coupling said source to said transducer, one lead of said transformer being directly connected to one lead of said transducer; a first resistor serially connected between the other lead of said transformer and the other lead of said transducer; a switching network connected in parallel with said first resistor, said switching network including a switch having a plurality of switching positions; and means in said switching network for placing an electrical short circuit about said first resistor when said switch is in said first position, whereby no signal attenuation is experienced by said transducer, and for removing said electrical short circuit and introducing successive combinations of series and parallel resistances, each including said first resistor, between said source and said transducer when said switch is moved to successive ones of said plurality of switching positions, whereby the power available to said transducer is successively varied.
- 10 25 2. The combination of claim 1, wherein one of said successive ones of said plurality of switching positions includes a connection to said one lead of said transducer whereby a direct short circuit is placed across said transducer.
- 30 3. In combination; a source of electrical signals including an output transformer having two leads; a transducer for converting said electrical signals into corresponding acoustic signals, said transducer also having two leads; a common connection between one lead of said transformer and one lead of said transducer; a first resistance element serially connected between the other lead of said transformer and the other lead of said transducer; a single pole switch, having a movable contact making arm and a plurality of stationary contact positions, arranged with said arm connected to said other lead of said transducer; a first one of said stationary contacts being connected to said other lead of said transformer; a second resistance element connected between a second and a third one of said stationary contacts; a direct connection between said third stationary contact and said common connection; whereby, when said arm rests on said first contact said first resistance element is short circuited and said transducer is connected directly across said source, when said arm rests on said second contact said second resistance element is connected in parallel with said transducer and the combination connected to said source through said first resistance element, and when said arm rests on said third contact said transducer is short circuited and said first resistance element comprises the entire load for said transformer.
- 35 40 45 50 55 60 65 70 75 4. An arrangement for controlling electrical energy delivered to a load by a power source while maintaining a substantially constant impedance match with the power source comprising; a power source; a load; first resistor means electrically connected between one terminal of said power source and one terminal of said load; a common connection between the other terminal of said power source and the other terminal of said load; second resistor means electrically coupled to said common connection; a first switch having a first movable contact electrically connected to said one terminal of said load; a second multiple contact switch having a second movable contact; said first movable contact of said first switch being movable between a first position in which said first resistor means is short circuited and a second position in which said short circuit is removed and said first movable contact is electrically connected to said second movable contact; said second resistor means comprising a plurality of resistor elements; said second movable contact being

movable between a position in which it is electrically connected to said one terminal of said power source and a plurality of positions in which its movable contact is electrically connected to selected ones of said resistor elements whereby said selected resistor elements may be 5 arranged in parallel with said load when said first movable element of said first switch is in its second position.
